T. N. BADGER

MAIL RECEIVER

Filed June 30, 1924

Thomas N. Badger Inventor.

UNITED STATES PATENT OFFICE.

THOMAS N. BADGER, OF BERKELEY, CALIFORNIA.

MAIL RECEIVER.

Application filed June 30, 1924. Serial No. 723,409.

To all whom it may concern:

Be it known that I, THOMAS N. BADGER, a citizen of the United States, residing at Berkeley, in the county of Alameda and 5 State of California, have invented a new and useful Mail Receiver, of which the following is a specification.

My invention relates to improvements in a mail receiver; and the object of my improvements is to provide a mail receiver of non-corrosive metal, or other suitable material, that will easily pass the mail through the wall and land it secure in the building.

15 My mail receiver is water tight, wind tight, ornamental, indestructible, automatic, absolutely safe and in passing the mail it produces a bell-like sound announcing its arrival. It will securely hold letters to be mailed. The only working part, the door, may be removed and a new spring inserted without removing the box from its place in the wall.

20 My invention is illustrated by the accompanying drawing.

Fig. I shows a sectional view of the box and inside finish of wood.

Fig. II shows the front of the box with the door open, exposing the mechanical equipment that operates the door.

Going into detail of the drawings more explicitly;

1 is the shell made of metal or other suitable material forming the body of the mail receiver constructed to slope upward from the outside.

2 is a frame or facing serving as a stop for the door and as a finish for the exposed face of the box.

40 3 is the oscillating door.

4 is a coil spring of brass or other suitable material for keeping the door closed.

5 is a lug-like piece of metal supporting one end of axle 7.

45 6 is a lug on the door to carry the axle.

7 is an axle.

8 is a set screw holding the axle in place. The removal of this set screw releases the axles, the spring and the door.

50 9 is a screw to hold the box in place in the wall.

10 is a screw to hold the box in place in the wall.

11 is a screw to hold the box in place in the wall. 55

12 is one member of wood finish inside the building.

13 is one member of wood finish inside the building.

14 is inside plaster. 60

15 is a wooden collar surrounding the box placed to receive screws as shown in drawing. The collar is securely fastened to the sheathing.

16 is sheathing. 65

17 is outside plaster.

18 is one member of inside wood finish.

19 is a window seat, table, cabinet or the floor of the room.

20 is curve described by mail in its passage through from outside to inside. 70

21 is an adjusting strip of wood, its width depending on the thickness of the outside plaster. The details are so clearly shown that a very brief description of the operating of the box should be ample. 75

The box is made of two pieces of non-corrosive metal, or other suitable material, cast or sheet, namely the body proper and the door (with brass, or other suitable material, springs, axles, and set screws). These parts are assembled and the box shoved through the wall from the outside and secured to the building by four brass screws, 9, 10 and 11. 10 representing a 80 screw on each side of the box. The mail is shoved through and the door automatically closes, ad infinitum.

I wish it understood that various changes in form and proportion may be resorted to 90 within the scope of the appended claim, similarly that the materials and finish of the several parts employed may be such as the experience and judgment of the manufacturer may dictate or various uses may demand. 95

Having fully described my invention, I claim and desire to secure by Letters Patent:

A mail receiver comprising connected 100 side, top and bottom sections, said sections forming an elongated box rectangular shaped in cross section, a door hingedly secured to the bottom section and movable towards the bottom section when opened, a 105 spring co-operating with the door hinge and

normally maintaining the door in a vertical position, and a frame secured on one end of the box, said frame forming a sounding member and a stop to prevent movement of the door beyond a vertical position in one direction; said elongated box having a step down at the outer end of the lower side

forming a recess to be used in placing the operating mechanism of the door, and having means whereby the door, springs and axes may be assembled in place or disassembled at will, leaving the fixed elongated body of the box undisturbed.

THOMAS N. BADGER.
